Samuel Ulieman

ATTORNEY

UNITED STATES PATENT OFFICE

ARTHUR K. LAUKEL, OF DETROIT, MICHIGAN

COPE AND DRAG PLATE

Application filed December 29, 1928. Serial No. 329,221.

In my United States Patents No. 1,570,634 of January 26, 1926 and No. 1,649,312 of November 15, 1927 and my co-pending application Serial No. 108,715, filed May 13, 1926, I have disclosed means and methods of producing pattern equipment by the electrodeposition of metal on a mold or matrix taken from the object to be reproduced. In the application of these inventions to cope and drag plates with regular or irregular partings, for use in molding machines, there arises the problem of providing suitable carrying and backing means for the electrodeposited molding surface. It will be understood in this connection that, in the interest of economy of time and material consumed in the plating operation, the deposit should be made no thicker than necessary to maintain its form during manipulation after removal from the bath. A suitable reinforcing means for the deposit therefor is necessary.

The object of the present invention is to provide a construction for cope and drag plates satisfying the conditions set forth. It may be stated that a part of the face of the pattern is not molding surface but merely facing, and this part is preferably provided in the nature of a machined face plate attached to the mold or matrix prior to immersion in the bath and to which the deposit firmly adheres. This face plate preferably includes locating members, such as apertured ears, for co-operation with corresponding locating members in the flask of the molding machine.

After removal of the plated mold from the bath, a suitable back is secured to the reverse side of the face plate, and a filling material such as magnesium oxychloride cement is packed into the space between the back and the deposit. It will be seen as the description proceeds that this method is applicable equally to regular and irregular partings.

The invention is fully disclosed by way of example in the following description and in the accompanying drawings in which

Figure 1 is a fragmentary plan view of a mold taken from a manifold of a gasoline

engine, and having the face plate applied thereto;

Figure 2 is a cross sectional view of the mold with the deposit thereon, corresponding to a section on the line 2—2 of Figure 1;

Figure 3 is a similar view showing the deposit partly filled and the back laid upon the face plate;

Figure 4 is a similar view showing the face plate attached to the back and the latter completely filled;

Figure 5 is a similar section showing the completed pattern removed from the mold and facing upwards; and

Figure 6 is a perspective view of the cope or drag plate.

Reference to these views will now be made by use of like characters which are employed to designate corresponding parts throughout.

In Figures 1 and 2 is illustrated a mold or matrix 1 formed, after the fashion of a plaster match in ordinary pattern making, over the pattern to be reproduced which may be of wood, metal or even plaster. The preparation of this mold, including the formation of the conducting surface and treatment to resist deterioration in the bath, is fully disclosed in the above mentioned patents and application.

Inasmuch as the marginal portion of the face of a cope or drag plate is a plane surface or combination of plane surfaces, the same need not be deposited but may be provided in the nature of a face plate or framing member 3 surrounding the impression 4 to be plated. In the case of a regular parting, it is obvious that the face plate lies in one plane; and in order to demonstrate the applicability of the invention to irregular partings, the mold 1 is illustrated as having high and low parts 5 and 6 respectively with a step or incline 7 therebetween. In such cases the face plate is made up of separate strips terminating at the ends of the several planes determined according to the irregular parting as indicated by the lines 8 in Figure 1. These strips are secured to the mold by screws 9 passed into drill holes 10 formed from the back of the mold, the screws being passed

100

through the mold and threaded into the strips which have been previously tapped for the purpose. The inner edge of the face plate is bevelled as at 11, and the bevelled edge is corrugated transversely as at 12 for reception of the deposit 13. The bevelled edge prevents the deposit from being pulled out of the face plate in the use of the pattern, and the corrugations increase the area of contact and hence the adhesion between the face plate and deposit. The various depths of the impression in the mold 1 are designated by the corresponding characters *a*, *b*, *c*, and *d* in Figures 1 and 2.

15 After removal of the mold 1 with the deposit thereon from the bath, a backing member is laid upon the face plate and fitted thereto. This member includes an enclosing wall 15 with a partition generally parallel to the face plate and having high and low portions 16 and 17 respectively over the high and low portions of the face plate, with an incline or step 18 therebetween. The back member is, moreover, braced or reinforced 20 by webs 19 on the outer side of the partition as shown in Figure 6. The contacting edge 20 of the back is fitted accurately over the face plate so that it lies flat and firmly thereon. The deeper parts of the pattern may be filled 25 with material 21 prior to permanently attaching the back to the face plate in the manner presently to be described.

The filling material is preferably one capable of being poured cold, for it has been found 30 that a hot pouring substance causes the deposit and backing member, which are different metals, to expand unequally, as a result of which the congealing filler adheres to and binds the backing member and deposit before 35 they have fully contracted, thus causing warping. In order to avoid this difficulty, the filling material should be a durable cold cement capable of withstanding the jolting in a modern molding machine, and it has been 40 found that magnesium oxychloride cement satisfies these requirements.

When the back 15—20 has been fitted on the face plate in the manner indicated, it is 45 clamped thereto by means of wood clamps or the like engaging also the bottom of the mold, and the screws 9 are removed. The contacting edge of the back is spotted or marked by a suitable instrument inserted through the screw holes formerly occupied by the screws 50 9. The back is now lifted so that it may be tapped as at 22 at the spots in registration with the screw holes in the face plate. After being tapped, the back is remounted on the 55 face plate in its fitted relation thereto, and the parts are permanently secured together by screws 23 countersunk in the face plate and threaded into the tapped holes 22. The remainder of the space between the deposit 13 60 and the partition 16—18 is rammed with more

filling material through holes 24 in the partition.

The mold 1 is now broken away from the deposit, and additional screws may be driven through the face plate into the back if desired. 70 Also, the intermediate parts of the deposit may be tied to the back by longer screws 25 having their heads countersunk in the deposit and their free ends threaded into the partition 16—18 as shown in Figure 5. Holes 75 may be formed in the cement for the screws 25 by positioning dummy pins between the deposit and partition prior to the first introduction of the cement 21.

It will be seen in Figure 1 that the face plate 3 is formed, preferably at its shorter edges, with lugs or ears 26 apertured at 27 to register with locating pins on the flask or molding machine to which the cope or drag plate is to be applied. The apertures 27 are located preferably during the mounting of the face plate on the mold and with due regard to the relation of the cope and drag plates to the flasks and to each other. The edge 20 of the back also has lugs 28 superimposed upon the lugs 26 and drilled at 29 in line with the apertures 27.

Although a specific embodiment of the invention has been illustrated and described, it will be understood that various alterations 95 in the details of construction may be made without departing from the scope of the invention as indicated by the appended claims.

What I claim is:—

1. A cope or drag plate comprising a face plate, an electrodeposited reproduction of the molding surface of a pattern secured within said face plate, a backing member fitted on the back side of said face plate and secured thereto, and a filling material confined within said backing member and reinforcing said reproduction. 100

2. A cope or drag plate comprising a face plate, an electrodeposited reproduction of the molding and parting surface of a pattern secured within said face plate, a backing member fitted on the back side of said face plate and secured thereto, and a filling material confined within said backing member and reinforcing said reproduction. 110

3. A cope or drag plate comprising a face plate, an electrodeposited reproduction of the molding surface of a pattern secured within said face plate, a backing member fitted on the back side of said face plate and secured thereto, and a cement confined within said backing member and reinforcing said reproduction. 120

4. A cope or drag plate comprising a face plate, members on said face plate for locating the same with respect to a flask, an electrodeposited reproduction of the molding surface of a pattern secured within said face plate, a backing member fitted on the back side of said face plate and secured thereto, 125

and a filling material confined within said backing member and reinforcing said reproduction.

5. A cope or drag plate comprising a face plate, members on said face plate for locating the same with respect to a flask, an electrodeposited reproduction of the molding surface of a pattern secured within said face plate, a backing member fitted on the back side of said face plate and secured thereto, a filling material confined within said backing member and reinforcing said reproduction, and locating members on said backing member and coinciding with said first named locating members.

6. An element of pattern equipment comprising a face plate defining an enclosure and having its inner edge beveled and corrugated transversely on the bevel, an electrodeposited reproduction of the molding face of a pattern element disposed within said face plate and having its marginal portion plated against said beveled and corrugated edge of the face plate.

25 7. An element of pattern equipment comprising a face plate defining an enclosure and having its inner edge beveled and corrugated transversely on the bevel, an electrodeposited reproduction of the molding face of a pattern element disposed within said face plate and having its marginal portion plated against said beveled and corrugated edge of the face plate, a backing member fitted on the back side of said face plate and secured thereto, 35 and a filling material confined within said backing member and reinforcing said reproduction.

40 8. An article of manufacture comprising a face plate forming an enclosure and having its inner edge beveled and corrugated transversely on the bevel, an electrodeposited reproduction of a face of a model disposed within said face plate and having its marginal portion plated against said beveled and corrugated edge.

45 9. The method of building a cope or drag plate consisting in forming a cast or matrix from a surface to be reproduced, preparing said matrix for immersion in an electrolytic bath and for plating on the impressed surface thereof, applying a face plate to the impressed surface of the matrix and around the impression on said surface, plating on said impressed surface and against said face plate, fitting and securing a box-like backing member on the back side of said face plate, and packing a cement into said backing member and against the reverse side of the deposit.

50 10. The method of building a cope or drag plate consisting in forming a cast or matrix from a surface to be reproduced, preparing said matrix for immersion in an electrolytic bath and for plating on the impressed surface thereof, applying a face plate to the impressed surface of the matrix and around the

impression on said surface, plating on said impressed surface and against said face plate, fitting and securing a box-like backing member on the back side of said face plate, packing a filling material into said backing member and against the reverse side of the deposit, and finally removing said face plate, deposit and filling material in assembled form from said matrix.

70 75 In witness whereof I have hereunto set my hand.

80 ARTHUR K. LAUKEL.
